AQUARIUM PUMP

Minnie Ovrutsky, Jackson Heights, N. Y.

Application April 26, 1957, Serial No. 45,911

Term of patent 7 years

(Cl. D65—1)

Figure 1 is a plan view of an aquarium pump embodying features of the present invention, and

Figure 2 is an elevational view of the aquarium pump shown in Figure 1.

The sides of the aquarium pump not disclosed in the drawing are like the side shown in the drawing.

I claim:

The ornamental design for an aquarium pump substantially as shown and described.
